ELECTRODE HOLDER

Norman J. Hoenie and Frank Malner, Cleveland,
Ohio, assignors to The Lincoln Electric Com-
pany, Cleveland, Ohio, a corporation of Ohio

Application July 11, 1938, Serial No. 218,590

6 Claims. (Cl. 219—8)

This invention relates, as indicated, to electrode holders.

It has as its principal object the provision of electrode holders which are of simple, rugged construction, consisting of a minimum number of easily manufactured and quickly assembled parts.

Another object of the invention is to provide an electrode holder which can be readily and quickly connected to the source of current supply without the use of special tools, such as wrenches, screw drivers, etc.

A further object of the invention is to provide an electrode holder which is of completely insulated construction, whereby the holder may 15 be laid on a metallic surface without danger of short-circuiting.

To the accomplishment of the foregoing and related ends, the invention, then, comprises the features hereinafter fully described, and particularly pointed out in the claims, the following description and the annexed drawings setting forth in detail certain illustrative embodiments of the invention, these being indicative however, of but a few of the various ways in which the principle of the invention may be employed.

In said annexed drawings:

Fig. 1 is a side elevational view of one form of electrode holder embodying the principal features of the invention; 30

Fig. 2 is a vertical longitudinal cross-sectional view of the holder;

Fig. 3 is a horizontal longitudinal cross-sectional view of the holder, taken on the line 3—3 35 of Fig. 2;

Fig. 4 is a transverse cross-sectional view of the holder, taken on the line 4—4 of Fig. 2;

Fig. 5 is a transverse cross-sectional view of the holder, taken on the line 5—5 of Fig. 2;

Fig. 6 is a fragmentary view, similar to Fig. 1, but showing the jaws of the holder partially open and grasping an electrode;

Fig. 7 is a plan view of a modified form of holder;

Fig. 8 is a vertical longitudinal cross-sectional view, taken on the line 8—8 of Fig. 7;

Fig. 9 is a transverse cross-sectional view, taken on the line 9—9 of Fig. 8;

Fig. 10 is a transverse cross-sectional view, taken on the line 10—10 of Fig. 8; and

Fig. 11 is a transverse cross-sectional view, taken on the line 11—11 of Fig. 7, but showing the jaws partially open and grasping an electrode.

Referring more particularly to that form of the invention shown in Figs. 1 to 6 inclusive, the holder will be seen to comprise a base member 1 of generally channel-shaped cross-section, the flanges 2 of which are shaped to provide ears 3

providing bearings for a shaft or pin 4. The forward portion of the web of the base member 1 is apertured as at 5 to receive the tenon 6 of a stationary jaw 7, the jaw being rigidly secured to said base member by riveting or peening the tenon to the lower surface of the base member. As seen in Fig. 3, the jaw 7 extends entirely across the space between the flanges 2, and, as seen in Fig. 1, the flanges at this point are cut 10 away to expose the jaw. The jaw 7 has formed in its upper surface a series of V-shaped grooves or recesses 8 and a groove or recess 9 which extends diagonally across the jaw and intersects the grooves 8.

The pin 4 forms a fulcrum for a pivotally movable lever 10, which is bent or curved near its forward end as at 11 to conform with the peripheral surface of the pin. The lever 10 has affixed to its rear end a tubular handle 12 formed of a suitable insulating material, such as hard rubber or the like.

Frictionally secured to the rear portion of the base member 1 is a tubular handle 13, also formed of insulating material, such as Bakelite or the like, the holder being held and manipulated by means of such handle.

Secured to the web of the base member 1, as by means of a bolt 14 and nut 15 is a flexible braided copper conductor 16; which is bent upwardly near its forward end, directly ahead of the curved portion 11 of lever 10, to provide a terminal portion 17 which is brazed to the lower surface of the forward portion of the lever. A movable jaw 18 is brazed to the lower surface of the terminal portion 17 of the conductor, and the lower surface of this jaw is grooved similarly to the jaw 7.

The jaws 7 and 18 are normally maintained in closed position by means of a coil spring 19, which is interposed between the conductor 16 and the lever 10 at a point rearwardly of the pin 4. The spring 19 is maintained against displacement by means of screws 20 and 21 which extend through the base member and lever respectively and into the ends of the spring.

The conductor 22, whereby the electrode holder is energized, extends through an opening 23 in the rear of the handle 13 and along the web of the base member 1, being provided at its forward end with a loop 24, which encircles the shank of the bolt 14, and is maintained in contact with the conductor 16 by the nut 15. A lock-washer 25 is interposed between the head 26 of the bolt 14 and the base member 1. The head 26, it may be noted, has an opening 27 therethrough which is just large enough for the insertion therethrough of a weldrod W (Fig. 5). Since the operator does not ordinarily carry a wrench or screw driver on his person, but does 50 55 60 have a supply of weldrods, the provision of the

opening 27 permits him to insert a weldrod there-through, as shown in Fig. 5, and to turn the bolt 14, so as to permit attachment and detachment of the conductor 22 from the holder. Moreover, the parts are so designed that the weldrod will bend before the threads of the bolt 14 will be stripped, so that a gauge is thus provided for insuring that the connections are just tight enough. In order to insert a weldrod in the holder, the operator will depress the lever 10 sufficiently to open the jaws and then position the weldrod in the grooves 8 or 9, as may be desired, thereafter releasing the lever, so that the parts will assume the position shown in Fig. 6.

The holder is thus seen to be of simple rugged construction, and to consist of a minimum number of easily manufactured and quickly-assemblable parts. The jaws are firmly secured to their respective backing members, and the flexible conductor 16 is secured in a highly desirable manner to the jaw 18 and lever 10. The lever 10 is secured in pivotal relation to the base member in such a manner as to dispense with the provision of sleeves and bearings which would run up the cost of the holder, and at the same time, the lever can be removed by the simple expedient of removing the spring 19, and then slipping the lever rearwardly below the pin A.

Referring now to the modified form of holder shown in Figs. 7 to 11 inclusive, this holder is of the completely insulated type, that is to say, it is so designed that it may be laid down, even when energized, on a metallic surface, without danger of short-circuiting, provided, of course, it is not laid down with a weldrod therein.

In this form of the holder, the base member 1' is also of generally channel-shaped form, and has frictionally secured thereto a tubular handle 13' of insulating material. The jaw 7', in this case, has inclined sides and is held in place by the flanges 2' of the base member, which are turned inwardly so as to form a dove-tail connection with the jaw. The jaw is insulated from said base member and flanges by means of insulation 30, formed of fiber board or the like. A bus-bar conductor 31 is interposed between the jaw 7' and insulation 30, and this bus bar extends rearwardly to a point just within the forward end of the handle 13', the intermediate portion of the bus bar being wrapped in insulating material 32, so as to insulate the same from the base member. The rear exposed portion of the bus bar and the bolt 14' and nut 15' are insulated from the base member by means of a channel-shaped strip 33 of insulating material, such as fiber board or the like. The head 26' of the bolt 14' is encased in a sleeve 34 of insulating material, this sleeve having apertures in its side, which are aligned with the opening 27', so that a weldrod may be inserted to turn the bolt, as in the previously described form of holder.

The spring 19', is, in this case, maintained in position by means of a screw 21 and a pin 35 which extends from a bridgepiece 36, extending between and secured to the flanges 2' as by welding or the like.

The forward end of the lever 10 is, in this case, provided with inwardly turned flanges 37 which have a dove-tail connection with the upper jaw 18' of the holder, the jaw being insulated from the lever by means of insulating material 38, such as fiber board. As seen in Fig. 11, it will be noted that the inner faces of the jaws 7' and 18' are so spaced from the flanges 2' 75

and 37 that the weldrod W cannot touch such flanges.

The holder is further provided with a shield or guard 39, which is secured to the handle 13', as by rivets 40.

It is thus seen that the holder is of such construction that the current-carrying parts are completely insulated from the exposed parts of the holder, so that the holder may be laid down on any surface without fear of short-circuiting.

Other modes of applying the principle of the invention may be employed, change being made as regards the details described, provided the features stated in any of the following claims, 15 or the equivalent of such, be employed.

We therefore particularly point out and distinctly claim as our invention:

1. In an electrode holder, a base member and a lever member angularly movable in relation to each other, and jaws carried by said members, said jaws being electrically insulated from said members.

2. In an electrode holder, members angularly movable in relation to each other, jaws secured to said members and insulated therefrom, and a current conductor secured to one of said members and insulated therefrom, said conductor having a portion interposed between the jaw carried by said member and the insulation therefor.

3. In an electrode holder, members angularly movable in relation to each other, jaws secured to said members and insulated therefrom, and a current conductor secured to one of said members and insulated therefrom, said conductor being in electrical contact with said jaw carried by said member.

4. In an electrode holder, a channel formed base member and a lever member angularly movable in relation thereto, a jaw held in the channel at one end of said base member, and a jaw on said lever member adapted to engage said first-named jaw, said jaws being respectively electrically insulated from said members.

5. In an electrode holder, a channel formed base member and a lever member angularly movable in relation thereto, a jaw held in the channel at one end of said base member, a jaw on said lever member adapted to engage said first-named jaw, said jaws being respectively electrically insulated from said members, and a conductor disposed in the channel of said base member and electrically connected with the said jaw carried by said member, said conductor being electrically insulated from said member.

6. In an electrode holder, a channel formed base member and a lever member angularly movable in relation thereto, a jaw held in the channel at one end of said base member, a jaw on said lever member adapted to engage said first-named jaw, said jaws being respectively electrically insulated from said members, and a conductor disposed in the channel of said base member and electrically connected with the said jaw carried by said member, said conductor being electrically insulated from said member, and means for securing a second conductor to said first-named conductor, said means comprising a bolt and a nut threaded thereon, the head of said bolt having an opening therethrough of a diameter sufficient to permit the insertion of an electrode, said head also having a covering of insulation.
